UNITED STATES PATENT OFFICE.

ANDREW J. ANDERSON AND GUS W. ANDERSON, OF GALESBURG, ILLINOIS.

CAN-OPENER.

1,249,586.

Specification of Letters Patent. Patented Dec. 11, 1917.

Application filed May 1, 1917. Serial No. 165,770.

To all whom it may concern:

Be it known, that we, ANDREW J. ANDERSON and GUS W. ANDERSON, citizens of the United States, residing at Galesburg, in the county of Knox and State of Illinois, have invented a new and useful Can-Opener, of which the following is a specification.

This invention relates to can openers, one of its objects being to provide a device of 10 this character especially useful in removing the ends of cans by cutting through the walls thereof, whether the cans be round or angular, thereby permitting the contents of the cans to be removed bodily.

15 A further object is to combine with a can opening blade, a novel form of slidable grip for engaging the can so as to hold the blade in proper position to cut.

Another object is to provide a can gripping element which, when not in use, serves 20 to protect the point of the cutting blade.

A still further object is to provide a can gripping element having means for automatically resetting it after each cutting operation.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:—

Figure 1 is a perspective view of the can 40 opener.

Fig. 2 is a plan view thereof, a portion of the handle being broken away.

Fig. 3 is a section on line 3—3 Fig. 2.

Referring to the figures by characters of 45 reference 1 designates a handle having a ferrule 2 which extends across one end thereof. Extending from the handle and the ferrule is a blade 3 the free end portion of which is provided with an obliquely disposed cutting edge 4 terminating in a point 5. This blade has a longitudinal slot 6.

Straddling the blade 3 are the arms 7 and 8 of a gripping element, these arms being extended from a saddle 9 which normally 50 overhangs the edge 4 and is provided, at its free end, with oppositely extending wings

10 each of which is provided, in its lower edge, with an angular recess or notch 11. The two arms are connected by rivets 12 or the like extending through the slot 6 and 60 adapted to slide longitudinally of the slot.

A stem 13 is arranged along one side of the blade. One end of this stem is extended laterally as at 14 and secured within one of the arms, 7, while the other end of the stem 65 is slidably mounted in the end of the ferrule and in the handle 1, there being a recess 15 provided therefor. A coiled spring 16 is mounted on the stem and bears at one end against the ferrule and at its other end 70 against the laterally extending end of the stem. This spring serves to hold the saddle 9 normally projected forwardly so as to overhang the point 5 of the blade.

Projecting outwardly from that end of 75 the arm 8 remote from the saddle 9 is a bottle cap remover 17 which can be of any desired configuration.

A can opener such as herein described is especially useful for cutting through the 80 sides of a can close to the top thereof, thus permitting the entire end of the can to be removed, so as to allow the contents of the can to be bodily removed. In using the can opener in this manner, the point 5 is forced 85 into the side of the can close to the end thereof, and the edge of the top of the can thus permitted to rest in one of the notches 11. The wings 10 will tightly grip the can while the blade 3 is being swung outwardly and 90 the edge 4 is cutting into the can, this blade traveling forward during the cutting operation, while the wings 10, by reason of their frictional engagement with the can, will be held against forward movement, thus 95 placing spring 16 under compression. As soon as the blade 3 is swung back to give a new purchase and to advance it farther along the can, the saddle 9 will be shifted forwardly by the spring 16, thereby bringing 100 the wings 10 to another position.

Obviously by having this gripping element mounted in the manner described, it will limit the depth to which the blade can be inserted into the can. By pulling back- 105 wardly on the part 17, the saddle 9 can be removed from above the edge 4 so that said edge can be easily sharpened.

While this device is particularly useful in cutting through the sides of a can, 110 whether angular or round, it can also be used for opening a can in the ordinary

manner, to wit, through the top thereof. Obviously, where the can is angular, it is possible, by providing the grip arrangement herein described, to cut up to the angle, because the wings 10 can be caused to engage the can at points back from the angle while the point 5 is projected therebeyond.

What is claimed is:—

- 10 1. A can opener including a blade having an obliquely disposed cutting edge terminating in a point, a gripping element slidably mounted on the blade and including oppositely extending can engaging wings and yielding means for holding the wings normally pressed to position adjacent the point of the blade.
- 20 2. A can opener including a blade having an obliquely disposed cutting edge terminating in a point, a gripping element slidably mounted on the blade and including oppositely extending can engaging wings, and yielding means for holding the wings normally pressed to position adjacent the point of the blade, said wings having can receiving notches.
- 30 3. A can opener including a blade having an obliquely disposed cutting edge terminating in a point, a saddle, yielding means for holding the saddle normally in position opposite the said edge, arms extending from the saddle and straddling the blade, co-operating means upon the arms and blade for guiding the saddle, said saddle being

slidable relative to the blade, and can gripping members extending from the saddle.

4. A can opener including a blade having an obliquely disposed cutting edge terminating in a point, a saddle, yielding means for holding the saddle normally in position opposite the said edge, arms extending from the saddle and straddling the blade, co-operating means upon the arms and blade for guiding the saddle, said saddle being slid- 35 able relative to the blade, and can gripping members extending from the saddle, said members having a can receiving notch.

5. A can opener including a blade having an obliquely disposed cutting edge terminating in a point, said blade being longitudinally slotted, a saddle, arms extending from the saddle and straddling the blade, means connecting the arms and extending through and slidably mounted within the slot, a stem extending from one of the arms and slid- 50 able therewith, yielding means engaging the stem for holding the saddle normally positioned opposite the cutting edge, and a gripping wing extending from the saddle.

In testimony that we claim the foregoing as our own, we have hereto affixed our signatures in the presence of two witnesses.

ANDREW J. ANDERSON.
